H. Crenshaw,

Water Wheel,

Patented Dec. 28, 1832.

Dec. 28. 1832

385

Henry Branshaw
Benton Patent

The defendant referred to in this Process Patent and making part of the same containing a description in the words of the said Henry Branshaw himself, of his Improvement in Machinery, consisting in the repeated application of water to a number of wheels in succession called "Branshaw's Multiplied Water Power."

To all to whom these presents shall come. We it know that Henry Branshaw of the District of Columbia in the State of District Columbia have invented a new and useful improvement in machinery consisting in the repeated application of water to a number of wheels in succession the name of which invention may be "Branshaw's Multiplied Water Power" and that the following description of the construction and operation of the said Machinery as invented by me is as full as may be to illustrate the invention which consists rather in the principle of the repeated use of water on different wheels than in any peculiarity or novel construction in machinery. The object of the invention is to convert small streams of water into use in carrying all sorts of machinery as Loring, graining, and the like. To illustrate as near as possible the application of the principles of the Multiplied Water Power let it be supposed that we have a stream of water one foot wide and one inch deep having a fall of ten feet perpendicular. This fall of ten feet will enable the volume of water one foot by one inch to be carried down an inclined plane for about one hundred feet in length. This inclined plane may be a ravine which are to be placed small wheels (varying) from a foot to four feet in diameter, the velocity of the wheels being inversely as the size of them. The wheels are to run on their axles attached to upright posts on the sides of the bank or race. They are to have buckets or plain flasks fitted so that they may fill the same say one foot wide. In a fall of ten feet making an inclined plane of about one hundred feet, there may be from twenty five to one hundred of these small, round, flat wheels caused by the weight of some of the water descending, the water not a hand full from every one of these wheels to a knap, to which

1340

With all the force of each one of the small water wheels it is impossible that
a staff may occupy any convenient position above the small water wheel
and of the case, the great staff will have a work about one of great moment
and advantage for a great mill, as is the case for a great water wheel,
and this should have a heavy bottom wheel to prevent a strong position.
The above description is followed by a formula to which would correspond
the number in the size of the water wheel, in a stream of ten feet high and
one foot by one inch of volume, but it is necessary to be aware because of the
quantity of water in the fall of it an appropriate variation in the size and
number of the water wheels must follow. The model will be the following
so though sufficient in respect of the number of wheels, yet not fully
principles. The condition in case of the water to run in, the water wheel,
the staff having a balance wheel and running) of eight feet and the
same connecting the small water wheel with the staff, are all placed
in the model, besides also a work about to the machine to the use of a
new mill when in use. Now if however to find a quantity of water
to let the number of wheels on an average to be about one of the
mill or machine started, that the balance on the water wheel should
not be a water plant, but that it should only be a balance wheel so as to
with arms reaching to three feet. The great superiority of these numerous
small water wheels over one large water wheel of course is equal to that
of all the small wheel combined principally in the arrangement of which
is equally the desired velocity greater in turning, giving the. These
Note that the above case consideration is a case running and facts given, and
and further that I made the drawing of my first one on the first day
and much in December of the first year (1824)
